UNITED STATES PATENT OFFICE.

ERNEST B. GUSTOFSON, OF ANOKA, MINNESOTA.

GEARING.

1,305,716.

Specification of Letters Patent. Patented June 3, 1919.

Application filed June 24, 1918. Serial No. 241,575.

To all whom it may concern:

Be it known that I, ERNEST B. GUSTOFSON, a citizen of the United States, residing at Anoka, in the county of Anoka and State 5 of Minnesota, have invented certain new and useful Improvements in Gearing, of which the following is a specification.

This invention relates to gearing for cylinder washing machines and the object of 10 the invention is to provide simple and compact gearing whereby the cylinder of the machine will be given two complete revolutions in one direction and then two complete revolutions in the opposite direction, the 15 driving shaft rotating continuously in one direction. A further object of the invention is to simplify the means by which the driving shaft is thrown into or out of operative connection with the shaft of the washing 20 machine cylinder, and other incidental objects of the invention will appear in the course of the following description.

The invention is illustrated in the accompanying drawings in which—
25 Figure 1 is an end elevation of a washing machine having my improved gearing applied thereto;

Fig. 2 is a plan view of one end of the tub with the gearing in position thereon;

30 Fig. 3 is an elevation of a portion of the train of gearing;

Fig. 4 is a detail view of the frame;

Fig. 5 is a detail of a portion of the master gear;

35 Fig. 6 is a detail view of the gearing by which the driving shaft is operatively connected with the master gear.

The washing machine tub 1 is of the usual dimensions and is supported at its end 40 by a frame having legs or standards 2 which also supports the gearing by which the cylinder is caused to rotate within the tub. The standards are connected by an arcuate flange or web 40 which fits under and is secured to 45 the end of the tub and is provided at its center with a hollow projection 41 to which a discharge pipe may be fitted. Upon the outer side of the frame, at the rear thereof, I secure a bracket or frame 3 having an 50 outer arm 4 the upper end of which coacts with a cap plate 5 to provide a bearing for the outer end of the driving shaft 6, a single band pulley 7 being secured upon the said shaft and a belt 8 being trained around 55 the said pulley so as to impart motion there-

to from any convenient engine or prime mover. Upon the inner portion of the driving shaft 6, I secure a gear 9 which meshes with a gear 10 loosely mounted upon a stub shaft 11 extending between the branches 12 of a lever or swinging arm 13 which is fulcrumed at its rear end 14 upon the frame or bracket 3. The frame is provided at its rear edge with an upstanding post or plate 42 to which the bracket 3 may be secured 60 in any convenient manner and at the upper end of which is a socket or bearing 43 for the inner end of the driving shaft 6. A pinion 15 is also mounted on the shaft 11 and is fast to the gear 10, this pinion 15, when the 65 device is in operation, meshing with the external gear 16 on the periphery of the master gear wheel 17. The master gear wheel is loose upon a stub shaft 18 extending from the bearing 44 at the apex of the frame. 70 Upon its inner face, the master gear 17 carries an arcuate internal rack 19, which as the gear rotates, will mesh with and drive the pinions 20 and 21 alternately. These pinions 20 and 21 are disposed at substantially 75 diametrically opposite points with respect to the cylinder shaft and are secured upon shafts 22 and 23, respectively, which are mounted in bearings at the upper ends of arms, shown at 45, on the frame 2. Coaxial 80 with and fixed to the pinions 20 and 21, respectively, are gears 24 and 25, the gear 24 meshing with an idler 26, which, in turn, meshes with the gear 27 fixed to the cylinder shaft, while the gear 25 also meshes with 85 said gear 27. The cylinder shaft extends through the end of the tub in the usual manner and the extremity 46 of the shaft is disposed at the outer side of the gear 27 and journaled in the bearing 44 as indicated by 90 95 dotted lines in Fig. 2.

The lever or fork 13 has one of its branches projecting inwardly from the bracket or frame 3 and is equipped with a guide arm 28 extending downwardly in front of the said 100 bracket or frame 3. An angle lever 29 is pivoted to the lever 13 and the depending branch of this angle lever carries a bolt 30 which is slidably fitted in the guide arm 28 and is adapted to engage a suitable socket 105 or opening in the frame or bracket 3, whereby the lever 13 and the gearing carried thereby will be held in the operative position. A spring 31 is disposed between the front ends of the levers 13 and 29 so that the 110

bolt will be normally held in its operative position and will be held against accidental release from the bracket 3.

It is thought the operation of the mechanism will be readily understood from the foregoing description. The several parts are so proportioned that the master gear 17 will make one complete revolution to four complete revolutions of the cylinder shaft 10 or the gear 27. When the shaft 11 is in its upper forward position, the motion of the driving shaft will be transmitted through the gears 9, 10, and 15 to the master gear 17, as will be readily understood. The rack 19 15 on the master gear will be in mesh with one or the other of the pinions 20 and 21 during practically the entire rotation of the master gear but the extent of the rack is preferably a trifle less than one-half the 20 peripheral extent of the master gear so that the rack will leave one pinion before it meshes with the other pinion and will thereby avoid breakage of parts due to an attempt 25 of the cylinder shaft to rotate in opposite directions simultaneously. When the rack meshes with the pinion 20, the motion will be transmitted through the gears 24 and 26 to the cylinder gear 27 and said gear 27 will, consequently, rotate in one direction but 30 when the rack is in mesh with the pinion 21, the motion will be transmitted through the gear 25 directly to the gear 27 without the interposition of an idler and the said gear 27 will, therefore, rotate in a direction opposite to that derived through the idler 26. When it is desired to stop the operation of 35 the machine in order to change the contents of the tub or for any other purpose, the hand lever 29 is pressed upwardly against the tension of the spring 31 and the bolt or latch 30 is thereby withdrawn from the frame 3 so that the lever 13 may be swung rearwardly and the gear 15 moved out of mesh with the gear 17. The shaft 6 may then be permitted 40 to continue its motion or the motor may be stopped as may be more economical or desirable, but it is not necessary to stop the rotation of the driving shaft 6 in order to stop the machine nor is it necessary to reverse the 45 direction of the rotation of said shaft in order to reverse the motion of the washing 50

machine cylinder. My improved mechanism is exceedingly simple and compact and may be readily applied to any machines now in use. ⁵

Having thus described the invention, what is claimed as new is:

1. The combination of a master gear having a rack on one side, a driven gear disposed coaxially with the master gear, gears at opposite sides of the driven gear to be engaged by the rack, intermediate gears between the said gears and the driven gear whereby the driven gear will be caused to rotate alternately in opposite directions, a driving shaft, means for rotating the driving shaft continuously in one direction, and means for operatively connecting the driving shaft with the master gear or disconnecting it therefrom. ⁶⁵ ⁷⁰

2. The combination of a master gear, a driven gear, operative connections between the master gear and the driven gear whereby the driven gear will be caused to rotate alternately in opposite directions as the master gear rotates continuously in one direction, a driving shaft, a gear upon the driving shaft, a support adjacent the driving shaft mounted to swing in a plane parallel with the plane of the master gear, idler pinions carried by said support and arranged between and adapted to operatively connect the gear on the driving shaft with the master gear, and means for retaining said swinging support in the operative position. ⁷⁵ ⁸⁰ ⁸⁵

3. The combination of a main support, a bracket thereon, a driving shaft mounted in the bracket, a gear on the driving shaft, a master gear mounted loosely on the main support, a driven gear on the main support, ⁹⁰ intermediate gears whereby the driven gear will be caused to rotate alternately in opposite directions as the master gear rotates continuously in one direction, a swinging lever mounted upon the bracket, idler pinions carried by said swinging lever to operatively connect the gear on the driving shaft with the master gear, and a latch carried by said swinging lever and adapted to engage said bracket. ⁹⁵ ¹⁰⁰

In testimony whereof I affix my signature.
ERNEST B. GUSTOFSON. [L.S.]
